SHAFT KILNS

Henry Pooley, London, and Lionel Douglas Parker, Woking, England, assignors to Vickers-Armstrongs Limited, London, England, a British company

Application January 29, 1954, Serial No. 407,058

Claims priority, application Great Britain February 3, 1953

5 Claims. (Cl. 263—29)

This invention relates to shaft kilns for burning cement clinker, lime, or for the sintering of ores or for similar purposes.

Gas fired vertical shaft kilns in which the gas enters the kiln from side ports are known. Such kilns suffer the disadvantage that the heating gas is released directly into the material to be treated and combustion tends to be confined by the material to the periphery of the kiln. Consequently, uneven burning results due to the difficulty of transferring the heat from the periphery to the centre of the kiln. A further disadvantage lies in the fact that, due to the flame being entirely surrounded by material, local fusion of the material around the periphery of the kiln occurs, causing the downward flow of the material to be retarded. The high concentration of heat immediately adjacent to the arched brick lined gas inlets, causes excessive deterioration of the fire-brick lining at the inlet points, necessitating frequent stoppages for repairing the brick lining.

An oil fired shaft kiln has been proposed in which the oil for combustion passes down a central firing pipe from the top of the kiln into a burning zone. In this case also combustion is localised and uneven burning results due to the difficulty of transferring the heat from the centre of the kiln to the periphery. The same disadvantages occur when a kiln is gas fired by a central firing pipe. The known kilns also suffer the disadvantage that the burning conditions cannot be observed.

It is an object of the invention to provide a centrally fired shaft kiln in which the disadvantages mentioned above are eliminated or minimised.

According to the invention there is provided a shaft kiln in which there is located a material deflecting member, immediately beneath which a fuel burner is located for firing the kiln, and in which the shaft converges downwardly to a reduced cross-section at about the region of the deflecting member so that, when the kiln is in operation and material to be treated passes downwardly therethrough, a combustion chamber is formed defined by the deflecting member and the natural slope of the material therebeneath so that combustion occurs substantially over the entire reduced cross-section of the kiln.

For a better understanding of the invention and to show how the same may be carried into effect, reference will now be made to the accompanying drawings, in which:

Figure 1 is a sectional elevation of one constructional form of kiln,

Figure 2 is a sectional elevation of another constructional form of kiln,

Figure 3 is a fragmentary side elevation corresponding to Figure 2, and

Figure 4 is a fragmentary section of a modified form of kiln.

Referring now to the drawings, the constructional form of kiln shown in Figure 1 is provided with a feed portion generally indicated at 1, and a lower portion, generally indicated at 2. The wall 3 of the portion 1 converges at 4 so that the lower portion 2 has a smaller

2

diameter than the portion 1. An enclosed walkway 5 having a floor 6, extends through and across the feed portion 1 of the kiln. A firing pipe 7 passes through the floor 6 into a combustion chamber 8, the walkway 5 accommodating the feed pipe for said firing pipe 7. The floor 6 is provided with peep holes 24 also extending into the combustion chamber so that the interior of the chamber 8 may be viewed. The combustion chamber 8 is defined by a frusto-conical cap body 9 acting as a material deflecting member and the surrounding material closing the open end thereof as shown.

Beneath the member 9 several arched openings 10 are formed to allow the material to be treated to enter the kiln portion 2 beneath the chamber 8.

5 A fan or blower 11 is provided beneath the kiln, which fan forces air upwardly through the kiln to a chimney 12. The kiln is also provided with a number of material discharge locks 13 so that the material can be withdrawn from the kiln without interfering with the circulation of the air.

10 When the kiln is in use, the raw materials are fed through a hopper 14 and the kiln is fired by means of gas, oil or powdered coal through the firing pipe 7. The fuel is burnt in the combustion chamber and the heat is spread over the full cross-section of the kiln at the burning zone 15. Thus, an equal distribution of heat is ensured, resulting in more stable conditions and better burning. The material passes downwardly through the kiln and is discharged through the lock system 13. The air supplied by the fan 11 passes upwardly through the kiln and initially serves to cool the material to be discharged from the kiln, and later passes upwardly from the combustion zone and thus serves to pre-heat the material fed to the feed end of the kiln. The kiln has the 15 advantages that it can be fired with powdered coal, oil or gas and the amount of fuel can readily be controlled. Due to the presence of a combustion chamber, the flame and burning conditions are visible and as already stated there is better distribution of heat over the whole cross-section of the kiln.

20 In the other constructional form, corresponding parts will be designated by the same reference numerals. In the constructional form shown in Figure 2, the air circulation is modified. A fan 16 draws air from the cooling zone of the kiln through the ports 17 located in the lower portion of the kiln, and draws air into the kiln through adjustable air inlets 17A located beneath the kiln. The air drawn from the kiln by the fan 16 is delivered as combustion air to a pipe 18 surrounding the firing pipe 7 or delivers primary air to the pipe 18 and secondary air to ports 18A. A second fan 19 draws the combustion gases down the kiln through the ports 20 situated beneath the burning zone of the kiln and thus the flame, in this constructional form, is drawn downwardly. At the same time the fan 19 also draws a portion of the air from the cooling zone of the kiln through the ports 20, such air entering the kiln through the adjustable cold air inlets 17A. The gases discharged by the fan 19 are delivered through a channel 21 into the pre-heating zone of the kiln above the combustion chamber and pass upwards to the chimney and thus pre-heat the material entering the kiln through the hopper 14.

25 The downward drawing of the flame has the advantage of preventing the fire brick arches surrounding the combustion chamber from becoming too hot. Adjustable cold air inlets 25 are also provided in the circulation of the fan 19 so that the temperature of the air handled by the fan and discharged into the pre-heating zone can be controlled to a certain extent. This kiln also has the advantage that powdered coal, oil or gas can be used and the amount of fuel is readily controlled. The flame and

burning conditions are visible as in the previous construction.

The through walkway may be omitted in both constructional forms of kilns. In that case, the firing pipe can extend downwardly through the kiln from above the kiln as shown in Figure 4, and peep-holes 24 are then provided as shown. The peep-holes 24 extend from the combustion through the wall 3 to the outside of the kiln.

We claim:

1. A centrally fired shaft kiln through which the material to be treated passes downwardly, said shaft kiln comprising a vertical shaft having an upper part, a lower part of reduced cross-section relative to that of the upper part and a short throat part converging sharply toward the lower part and connecting said upper and lower parts, a frusto-conical cap body having a convex face and supported in the shaft with its convex face directed towards the upper end of the shaft, said cap body being located in spaced relation to the side walls of the shaft at the lower end of said upper part adjacent the junction of the latter with said throat where it acts to deflect the material passing downwardly through the shaft, a fuel burner with its firing end extending into the cap body and arranged to introduce combustible fuel into the space under the cap body, feeding means located at the upper end of the shaft for supplying the material to be treated to the shaft, and discharging means located at the lower end of the shaft for discharging the treated material, said cap body and the deflected material therebeneath in said throat part of the shaft defining a combustion chamber in the central portion of the shaft within the material passing downwardly therethrough, whereby said lower part of reduced cross-section constitutes a treatment zone receiving the material from directly below the combustion chamber.

2. A shaft kiln as claimed in claim 1, including wall elements extending upwardly from the lower part of the shaft through the throat and supporting said cap body, said wall elements being spaced with respect to each other to provide conduit means through which the material to be treated descends from the upper part into the lower part of the shaft.

3. A shaft kiln as claimed in claim 1, further comprising an enclosed through-walkway extending across and through the upper part of the shaft at a location immediately above said cap body, said walkway accommodating part of the fuel burner.

4. A centrally fired shaft kiln through which the material to be treated passes downwardly, said shaft kiln comprising a vertical shaft having an upper part, a lower part of reduced cross-section relative to that of the upper part and a short throat part converging sharply toward the lower part and connecting said upper and lower parts, a material-deflecting member having a concave face and supported in the shaft with its concave face directed to-

wards the lower end of the shaft, said material-deflecting member being located in spaced relation to the side walls of the shaft at the lower end of said upper part adjacent the junction of the latter with said throat where it acts to deflect the material passing downwardly through the shaft, a fuel burner with its firing end extending into the material-deflecting member and arranged to introduce combustible fuel into the space under the material-deflecting member, feeding means located at the upper end of the shaft for supplying the material to be treated to the shaft, discharging means located at the lower end of the shaft for discharging the treated material, said material-deflecting member and the deflected material therebeneath in said throat part of the shaft defining a combustion chamber in the central portion of the shaft within the material passing downwardly therethrough, a first conduit means including a first blower supported outside the shaft, a first conduit connecting the intake of said first blower to a middle portion of said lower part to draw air into the blower from the lower end of the shaft, a second conduit connecting the outlet of the first blower to said upper part to supply primary air to the latter, said second conduit enclosing at its upper end the firing end of the burner to preheat the fuel therein and having a branch connection to the upper end of said lower part to supply secondary air thereto, a second conduit means including a second lower supported outside the shaft, a third conduit connecting the intake of said second blower to the shaft immediately above said first conduit to draw into the blower combustion gases pulled down the shaft and air from the lower end of the shaft, and a fourth conduit connecting the outlet of the second blower to the upper part of the shaft immediately above and around the material-deflecting member to preheat the material descending through the shaft into the combustion zone.

5. A kiln according to claim 4, further comprising valve means accommodated in the walls of said third conduit and extending therethrough to a location outside the shaft, whereby atmospheric air can be directly introduced into said third conduit for controlling the temperature of the gases therein.
